UNITED STATES PATENT OFFICE.

GEORGE McNEILL ROSE, JR., OF NASHVILLE, TENNESSEE.

TICKET OR RECEIPT CUTTER.

No. 906,295.

Specification of Letters Patent.

Patented Dec. 8, 1908.

Application filed March 27, 1908. Serial No. 423,515.

To all whom it may concern:

Be it known that I, GEORGE McNEILL ROSE, Jr., a citizen of the United States, and a resident of Nashville, in the county of 5 Davidson and State of Tennessee, have invented an Improvement in Ticket or Receipt Cutters, of which the following is a specification.

My invention is an improved device for 10 cutting and thus dividing receipts, or tickets, given for cash fares paid by passengers on railway trains. A series or pack of tickets or receipts, bearing indicia of different amounts or cash fares, is held in the device 15 and clamped in place by the cutters by which they are divided or severed transversely by the conductors, one portion thus cut off being handed the passenger. The several cutters employed are adjustable longitudinally 20 of the body of the device, so that they may be set in different positions corresponding to the amounts or sums of money in dollars, dimes, or cents for which the receipts are to be given.

25 The invention is embodied chiefly in the form, arrangement, and adaptation for adjustment of the several coacting cutters, as hereinafter described, and as illustrated in the accompanying drawing, in which

30 Figure 1 is a perspective view of my improved device, together with a pack or series of tickets or receipts held therein. Fig. 2 is a longitudinal section of the device together with the tickets or receipts. Fig. 3 is a 35 transverse section of the same. Fig. 4 is a plan view of the cutters and also the hinged plate to which they are secured, the same being shown disassociated or separate from each other. Fig. 5 is a plan view of a ticket 40 such as is employed in connection with the device proper.

The body, or back, 1 of the device is rectangular and oblong, and is preferably formed of thin sheet metal, which may be 45 cut out or struck up by means of dies, and is provided at the ends with upturned wings or flanges 2 and 2^a, for holding a pack of tickets or receipts in place. The rear side wings or flanges 2 and 2^a are provided with vertical 50 slots 3 to receive the pivots 4 of the plate 5 to which the cutters 6, 7, and 7^a are secured. The plate 5, together with the several cutters which are attached underneath the same, is adapted to lie upon the tickets or 55 receipts x, as indicated in the first three figures, but may be raised therefrom and at an

angle to the body 1, to enable the receipts to be placed in and removed from the holder. The function of the slots 3 is to permit the plate 5 to accommodate itself, and thus lie 60 parallel, to the tickets or receipts, whether the pack be thick or thin. The plate 5 has three slots 8, 9, 9^a. These slots are for the purpose of receiving studs 10, 10^a, and 11, fixed in the respective cutters 6, 7, 7^a, as 65 shown best in Fig. 4. These studs are provided with enlarged or roughened heads, as shown in the drawing. The studs 10, 10^a, of the two smaller and outer cutters, project up through slots 12, 12^a, in the broader or larger 70 cutter 6. The latter has a pointed, or arrow-head, shape, and the two bevels form sharp edges. The front ends of the side cutters 7, 7^a, are inclined at an angle of about 45° and also beveled to form a sharp cutting 75 edge. It will be observed that the cutters 6, 7, 7^a, may be adjusted independently of each other and the larger cutter 6; that is to say, they may be slid lengthwise of the 80 body 1 and plate 5. The side edges of the several cutters abut narrow flanges 13, formed on the sides of the hinged plate 5, and thus said flanges serve as guides for the several cutters in their longitudinal adjustment. 85

As shown in Figs. 1 and 5, the paper tickets or receipts proper are printed with transverse lines and numerals from 1 to 9 inclusive, to indicate dollars, dimes, and cents, In order to secure greater space upon a 90 comparatively narrow ticket or receipt, the lines are arranged at an angle of about 45° to each other, the dollars being indicated on the left, the dimes in the middle, and cents on the right. It will be observed that the angles of 95 the lines to each other correspond to the angles of the cutting edges of the several cutters.

In the practical use of my improved cutter, it is manipulated as follows: The device 100 should be held in the right-hand with the thumb of that hand on the two right-hand milled or roughened heads which are attached to the cutters 6, and 7^a, respectively. Then, with the thumb on the left-hand heads 105 slide the left-hand or dollar cutter 7 to the required position. Suppose the amount which the passenger has paid for a ticket is \$2.34. The left-hand cutter in that case will be adjusted to the dollar line marked 2. 110 Then, releasing the thumb of the right-hand, and pressing with the left thumb on the dol-

lar cutter 7, which has been adjusted, the central large dime cutter 6 is adjusted until its angular point corresponds with the lines indicated by 3 on the tickets x. The left 5 thumb is then moved to clamp both the cutters 6 and 7, and the right-hand cutter is next adjusted to the line 4. Then, as is obvious, the sum \$2.34 will be indicated on the several lines which coincide with the angles 10 of the three cutters. The next operation consists in raising the forward free end of the ticket and drawing it quickly and firmly backward, whereby the cutters sever it along the lines indicated by 2, 3, 4. The outer and 15 severed portion of the ticket is given to the passenger and constitutes his receipt for the fare paid.

It is to be understood that I do not restrict myself to three cutters, although this number 20 may be preferable, but two or four may be used; also that the zigzag lines may be designated hundreds, tens and units, or for dates.

The use of the device is not to be restricted 25 to railway receipts or tickets, but availed of whenever receipts are to be delivered and stubs retained. The blank end portions of the ticket or receipt, see Fig. 5, are for printed matter indicating the name of the 30 company, and of the railroad line, and any other matter which may be deemed necessary or appropriate.

The device, taken as a whole, is simple, light, cheap, and may be quickly and easily 35 adjusted, and supplies an obvious want.

What I claim is:

1. The improved device for the purpose specified, comprising a body for holding tickets and receipts, a plate hinged thereto and 40 provided with longitudinal slots, a cutter having an angular beveled end and adjacent or side cutters also having inclined and beveled ends, the three cutters having studs pro-

jecting through the slots of the plate and provided with enlarged heads for use in holding the cutters secured to such plate and for adjusting the same, substantially as described. 45

2. The improved device for the purpose specified, comprising a holder proper for a series of tickets or receipts, and a plate adapted to overlie the receipts, a series of three flat cutters secured adjustably to said plate and adapted to be adjusted longitudinally of the holder proper, the main cutter having an angular point which is beveled on each side, and the two side cutters having angular points which are beveled on the sides adjacent to the point of the main cutter, the several cutters having projections by which they 55 may be conveniently pushed for adjusting them in the required position, substantially as described. 60

3. The improved device for the purpose specified, comprising the body or receipt holder proper, a plate adapted to overlie the receipts, a series of three flat cutters secured to said plate, and adapted to be adjusted lengthwise of the same and the body of the holder, the main cutter having an angular point which is beveled on each side, and two side cutters having angular points beveled on the inner sides or adjacent to the main cutter, substantially as described. 70

4. The improved device for the purpose specified, comprising a holder proper having at its rear angles flanges 2^a, 2^a provided with vertical slots, the plate 5 having lateral hinges 4 adapted to slide in said slots, and cutters secured to said plate and adapted to lie flat upon the receipt packs or bundles of different thicknesses, as shown and described. 75
